ATTORNEY.

UNITED STATES PATENT OFFICE.

JOHN H. LE GRAND, OF ELDORADO, KANSAS.

HEADACHE-POST CONTROL FOR ELECTRIC OIL-WELL EQUIPMENT.

Application filed January 3, 1927. Serial No. 158,806.

My invention relates to a headache post control for electric oil well equipment.

The objects of my invention are as follows:

First: To provide a headache post control for double rated twin motor oil well drilling equipment which incorporates a mechanical arrangement that prevents the change of motor winding connections by means of the pole changing switch from one rating and speed to the other rating and speed, except at the off position of the motor control apparatus, thereby eliminating the destructive arcing at the contact fingers of the pole changing switch and also reducing the chances of abusive operation of the motors and their control.

Second: To provide a headache post control mechanism which will permit the change of rotor circuit control of the individual motors applied, that is to say, an increase or decrease or rotor circuit resistance of one motor with respect to the other by means of one lever.

These and other objects will hereinafter be more fully explained.

Referring to the drawings:

Fig. 1 is a side view of the controller.

Fig. 2 is a cross sectional view of Fig. 1.

Fig. 3 is a transverse view of Fig. 1 showing the clutch engaged for the operation of the controllers.

Fig. 4 is a view taken along line IV—IV in Fig. 2.

Fig. 5 is a view taken along the line V—V in Fig. 2.

Fig. 6 is a diagrammatical plan view of an oil well rig showing the motors and controllers operatively positioned.

Fig. 7 is an elevation of Fig. 6.

Fig. 8 is a detail view of the mounting scheme of the cam collar on the supporting spindle.

Fig. 9 is a detailed view of the hub of sheave 5.

The mechanism herein disclosed consists of a spindle 1, rigidly connected to what is known in the oil fields as a headache post 2 which is a part of the rig and in close proximity to the well. The said spindle has a toothed flange 3 integral therewith and functions as a bearing against the side of said post and held firmly thereto by means of a nut 4 threadedly engaging on the end extending through the post as shown in Figs. 2 and 3.

Rotatably mounted on the spindle is a

sheave 5 having a cable 6 wound thereon extending to and engaging on a sheave 7 as operating means for the controller 8. Integral with the hub of sheave 5 is a sleeve 9 on which is rotatably mounted a sheave 10 having wound thereon a cable 11 which extends to and engages on a sheave 12 as operating means for a controller 13. Rotatably mounted on the spindle 1 is a sheave 14 having wound thereon a cable 15, the said cable extending to and engaging on a sheave 16 as operating means for the pole changing switch 17.

The hub of the sheave 14 is provided with a plurality of radially extending teeth to engage with the radially positioned teeth of the flange 3 functioning as a clutch for a selected position of the sheave 14, the said sheave being manipulated by an arm 18 rigidly attached thereto and radially extending therefrom.

As a separating means for the said toothed members I have provided a helical spring 19 housed within the hub of sheave 14 as shown in Fig. 2. The said spring contacting the flange 3 and the base of the housing and being wound around the spindle is free to rotate with the sheave or remain stationary with the flange.

Positioned between the hubs of the sheaves 10 and 14 is a washer 20 keyed to and slidably engaging longitudinally on the spindle 1, as shown in Fig. 8. The said washer has a radially positioned curvature 21 in one side thereof to receive an extension 22 and a similar extension 22' on the extended portion 9 of the hub of sheave 5. The said extensions co-inciding with the curvature function as cams, the said cams function by rotating the sheaves 5 and 10 simultaneously or separately sliding the sheave 14 longitudinally on the spindle to engagement with the said toothed members as shown in Fig. 3.

Positioned between the hubs of sheaves 5 and 10 is a lever 23 having an eye rotatably engaging on the extension 9 of sheave 5 as shown at E in Fig. 2. Positioned on opposite sides of the lever are housings 24 and 25, the said housings having spring actuated pawls 26 and 27 to engage in notches 28 and 29 in the adjacent ends of the hubs of sheaves 5 and 10. The said pawls are reciprocated by rods 30 and 31 which are connected to pivotally mounted grips 32 and 33 by which means the sheaves 5 and 10 may be rocked simultaneously or independent of each other,

all of said wheels being held in proper working position by a nut 34 threadedly engaging thereon.

To operate the controllers herein disclosed 5 will be as follows:

The current will be neutralized by placing the sheaves 5 and 10 relative to each other as shown in Figs. 1 and 2, at which time the sheave 14 is disengaged by aligned registry 10 of the cam members separating the hub of sheave 14 by the medium of the said spring 19 from the toothed flange 3 making it possible to rock said wheel as desired. When 15 said wheel is rocked by drawing the arm 18 in the direction of the arrow A the rating of the pole switch 17 is reduced. Then by rocking the sheaves 5 and 10 by the medium of the lever 23 in the direction of the arrow C the clutch mechanism of sheave 14 is engaged at which time the controllers 8 and 13 are simultaneously operated starting the 20 motors 7' and 12' with a gradual increased speed. To reverse the motors the said lever 23 will be rocked in the direction of the arrow D gradually increasing the speed in 25 a reverse direction, but prior to this movement the current will be neutralized as before stated.

It will be understood that the control consists of a sheave 14 as variable rating or 30 changing of poles by rocking the arm as indicated by the arrows A and B. The sheaves 5 and 10 function as actuating means for variable speed and reversing the motors.

To vary the speed either one of the sheaves 35 5 or 10 may be moved independent of the other to acquire a desired speed. Then by rocking both of said sheaves simultaneously the speed is made to increase or decrease, 40 this capacity being required in drilling an

oil well when strata of different texture are encountered, and different speed of the drill bit is required to meet the condition. It is also useful in different operations such as 45 bailing, swabbing, pumping or drawing the casing.

Such modifications may be employed as lie within the scope of the appended claims.

Having thus described my invention, what I claim as new and desire to secure by Letters Patent is:

1. In a headache post control for electric oil well equipment, the combination of a headache post and a spindle attached thereto, a pair of sheaves rotatably mounted on said spindle, cables wound on said sheaves extending to and engaging with a pair of electric controllers, means to rotate the sheaves separately or simultaneously to control the electric current, a third sheave rotatably mounted on the said spindle, a cable wound on said sheave, said cable extending to and engaging with a pole changing switch and means to rotate the said sheave for variable rating.

2. In a headache post control for electric oil well equipment, the combination of an oil well derrick, of an electric power system, of a controlling means rotatably carried on a single pin attached to the derrick, the said controlling means comprising a variable speed and neutralizing means operated by a single lever and a variable rating controlling means operated by a single lever, and a locking means for a variable rating means until 75 first said means is placed on neutral, or the electric current broken thereby.

In testimony whereof I affix my signature.

JOHN H. LE GRAND.
